CLAMP USED IN CLAMPING PLASTIC BLOCKS TOGETHER IN PLANK CONSTRUCTION

Emory M. Wilmer, Chillum, and William P. Hunter, Silver Spring, Md.

Application September 25, 1950, Serial No. 186,666

2 Claims. (Cl. 144—303)

1

By way of explanation, it might be stated that in present day building construction, it is common practice to provide floor or roof supporting planks or beams constructed of blocks made of a light weight insulating aggregate, clamped together to provide the desired length, the blocks being held in position by clamps for a period of time required to properly set the layer of concrete used in forming the floor or roof surface.

The clamps commonly used in clamping the rod used in conjunction with the clamps, are of a type including jaws which become inoperative due to use, and frequently distort or bend the rods with which they are used, making it necessary to replace the rods and clamps.

It is therefore the primary object of the present invention to provide a clamp and connecting rod designed for clamping plastic blocks together in the formation of a plank or beam, which clamps may be readily operated, eliminating the danger of distorting the clamps or rods used with the clamps in tying the blocks together.

An important object of the invention is to provide a clamp of the type that may be used with rods of standard lengths, the arrangement and construction of the component parts of the clamp being such that the clamp may be secured to the rod in the construction of a plank or beam of any desired length, thereby eliminating the necessity of providing rods of various lengths in the construction of planks or beams of different sizes.

Still another object of the invention is to provide a clamp which may be readily and easily positioned and one which may be readily removed without danger of damaging the clamp or rod or plank under construction.

With the foregoing and other objects in view which will appear as the description proceeds, the invention consists of certain novel details of construction and combinations of parts, hereinafter more fully described and pointed out in the claims, it being understood that changes may be made in the construction and arrangement of parts without departing from the spirit of the invention as claimed.

Referring to the drawing

Fig. 1 is a perspective view illustrating a series of blocks positioned side by side, one of the end plates having been removed and the connecting rod and clamp located for securing the end plates together.

Fig. 2 is a longitudinal sectional view through a group of blocks assembled in the formation of a plank, with the clamp forming the subject matter of the present invention as positioned to hold the blocks together.

2

Fig. 3 is an enlarged sectional view through blocks, end plates and rod and clamp, the rod and clamp being clamped in relation with the blocks and end plates.

5 Fig. 4 is a sectional view through the rod illustrating the outer end of the clamp as positioned thereon.

Referring to the drawing in detail, the reference character 5 indicates clamping plates which are of lengths equal to the lengths of the blocks with which the clamping plates are used, the clamping plates being preferably constructed of channel bar material with their open faces disposed outwardly, when in use.

10 15 As shown, these clamping plates are provided with openings 6 which are disposed centrally of the plates and arranged above a line drawn longitudinally through the centers of the plates, so that the major portions of the plates are below the openings 6 so that the plates when clamped to the blocks will provide a support for the rod and clamp used therewith, balancing the plank constructed, lending to ease in handling the plank.

20 25 These clamping plates are positioned at the ends of a line of blocks, which in the present showing are indicated by the reference character 7, the blocks being formed with central openings 8 that align when the blocks are positioned side by side in the formation of a plank, the central openings accommodating the rod 9 forming a part of the clamp, constituting the subject matter of the present invention.

30 35 The blocks are provided with semi-circular grooves 8' in one of the respective edges thereof, the grooves of adjacent blocks aligning to receive the rods 9' that are cemented in place to lend rigidity to the finished product.

40 As clearly shown by Fig. 3 of the drawing, one end of the rod 9 is supplied with a threaded section 10 which is welded thereto, the threaded section 10 accommodating the nut 11 which is moved into close contact with the clamping plate 5, associated therewith.

45 50 The opposite end of the rod 9 extends from the clamping plate 5 at the opposite end of the row of blocks 7 used in the formation of the plank or beam, and this extended end of the rod 9 provides a support for the wedge indicated generally by the reference character 12. This wedge embodies identical semi-coned shaped sections 13 fitted on opposite sides of the rod 9 directly opposite to each other, as clearly shown by the drawing.

55 The tapered outer surface 14 of the wedge fits into the tapered cone 6 of the plate 5 with which it is associated, and cooperates with the nut 11

fitted on the threaded rod 10 in clamping the blocks of the row of blocks together.

Formed on the inner surfaces of the clamp sections are outwardly disposed teeth 15 which are so arranged that when the rod 9 has been properly positioned and the clamp sections properly positioned by tapping the outer ends of the sections, the teeth will be caused to bite into the outer surface of the rod 9, holding the clamp in position and insuring a close fit between the various blocks used in the formation of the plank.

In using the clamp forming the subject matter of the present invention, the clamping plates 5 are positioned at the ends of a column of blocks, and the rod 9 is passed through the openings of the clamping plates and central openings of the blocks, the nut being moved into contact with the clamping plate associated therewith.

The clamp sections 13 of the wedge 12 are now positioned on the rod 9 in a manner as shown by Fig. 3, and the wedge sections 13 are tapped with a tool such as a hammer driving the wedge sections into the opening 6 associated therewith, whereupon the teeth of the wedge bite into the pipe and hold the clamping plates firmly in position at the ends of the line or column of blocks being assembled.

If necessary a wrench may be used after the positioning of the wedge 12, to tighten the nut to exert the desired pressure on the clamping plates against the ends of the blocks.

After the blocks together with the clamp, have been placed in the formation of a plank for a building structure, a number of such planks are placed side by side providing a surface for supporting a layer of plastic material such as concrete or the like in the formation of a flooring or roof.

After the plastic surfacing material has properly set, it is only necessary to back off nut 11 to space it from the clamping plate associated therewith. The end of the rod 9 on which the nut 11 is positioned, may now be tapped in the direction of the wedge 12, which will cause the wedge 12 to move out of its opening, releasing the clamp whereby the clamp may be readily removed and the rod pulled through the various blocks and removed. The plates 5 will now become loose from the end blocks of the plank.

Because of the construction of the clamp and the rod as described, it is obvious that the clamp may be used in conjunction with rods of various lengths in the formation of planks of various lengths, eliminating the necessity of using and providing rods of a particular length for a particular length of plank.

It will further be noted that the clamp, because

of its rigid construction, may be used indefinitely without replacement, and the clamp may be used without danger of the clamp slipping to release the blocks, during the formation of a plank or beam.

Having thus described the invention, what is claimed is:

1. An apparatus for temporarily clamping hollow building blocks together in a row in the formation of building planks, comprising plates having openings, fitted against the end blocks of such row of blocks, a rod having a threaded end, extending through the openings of said plates and openings of the hollow blocks, a cone-shaped wedge slidably mounted on said rod, and positioned in the opening of one of said plates, said cone shaped wedge having means to lock on said rod, a nut on the threaded end of the rod bearing against the other plate, and said nut and cone-shaped member adapted to cooperate in drawing the plates towards each other clamping the blocks of the row of blocks together.

2. An apparatus for temporarily clamping hollow building blocks together in a row, in the formation of a building plank, comprising a rod, a member extending from the threaded end of said rod, plates having openings fitted against the end blocks of a row of blocks at opposite ends of the row of blocks, a sectional cone-shaped wedge having teeth, fitted around said rod directly opposite to each other, said wedge being extended into an opening of one of said plates with a wedge fit, and a nut on the threaded member engaging with the plate at one end of the row of blocks said nut cooperating with said wedge in drawing said plates against the end blocks of the row of blocks clamping said blocks together.

EMORY M. WILMER.
WILLIAM P. HUNTER.
